UNITED STATES PATENT OFFICE.

WILLIAM H. O'DWYER, OF NEW YORK, N. Y.

DESIGN FOR AN ASH-RECEIVER.

SPECIFICATION forming part of Design No. 23,110, dated March 13, 1894.

Application filed January 13, 1894. Serial No. 496,808. Term of patent 14 years.

To all whom it may concern:

Be it known that I, WILLIAM H. O'DWYER, a citizen of the United States, residing in the city, county, and State of New York, have invented a certain new and useful Design for Ash-Receiver, of which the following is a specification.

My production of design relates to trays or receptacles.

Figure 1, is a vertical sectional view of a tray or receptacle embodying my production of design, and Fig. 2, is a view in perspective thereof.

In appearance the bowl or body 1, is hollow or concaved on its inner side, as at 1^a, and on its outer or under side it is convex, as shown at 2. Said bowl or body is circular or round in shape or contour and is bounded on its upper edge by a circular rim 3, the position of which with respect to the bowl or body is horizontal. The said bowl or body 1, is further bordered or bounded by an upward or

vertical rim 4, the edges of which present a series of angles or notches 5. The design of the supporting legs or feet of the bowl or body 25 consists of several swan figures 7, 7, having their necks curved upwardly beneath the circular rim 3, and intersecting the same. The inner wing of the swan at the left is represented as turned down and disclosing to view 30 a hollow or vacant interior. Beneath the two swans, the outline of the rear portion of still a third swan is to be seen.

I claim—

The design for a tray or receptacle, substantially as herein shown.

In testimony whereof I have signed my name to this specification in the presence of two subscribing witnesses.

WILLIAM H. O'DWYER.

Witnesses:
